UNITED STATES PATENT OFFICE.

L. P. HARADON, OF INDEPENDENCE, IOWA.

IMPROVEMENT IN GRAIN-DISTRIBUTERS.

Specification forming part of Letters Patent No. 37,291, dated January 6, 1863.

To all whom it may concern:

Be it known that I, L. P. HARADON, of Independence, in the county of Buchanan and State of Iowa, have invented a new and Improved Grain-Distributing Device; and I do hereby declare that the following is a full, clear, and exact description of the same, reference being had to the accompanying drawings, making a part of this specification, in which—

Figure 1 is a side view of my invention. Fig. 2 is a plan or top view of the same; Fig. 3, a detached sectional view of a portion of the same, taken in the line *x x*, Fig. 2.

Similar letters of reference indicate corresponding parts in the several figures.

This invention relates to a new and improved device for distributing grain, chiefly from elevators, into different bins in the upper part of a building, the parts being so arranged that the grain may be discharged into different bins by adjusting the parts from the lower part of the building, thereby dispensing with the services of a person in the grain loft or apartment in which the bins to be filled are placed.

To enable those skilled in the art to fully understand and construct my invention, I will proceed to describe it.

A represents what may be termed a "telescopic tube," it being formed of a number of parts, *a b c*, which slide one within the other, as shown more particularly in Fig. 2. The part *a* of the tube is stationary, it being secured permanently to a proper framing, *B*, and in communication with the discharge-spout *C'* of a hopper, into which the grain is discharged from the elevators. The parts *b c* of the tube are attached to slides *d d*, which are fitted on the framing *B*, and allowed to work freely thereon, the slides being at the upper ends of the parts *b c*, the tube *A* and the upper part of the framing *B* having an inclined position, as shown clearly in Fig. 1.

To the lower end of the lower part, *c*, of the tube *A* there is attached a box, *C*, which is also allowed to slide freely on the framing *B*. This box *C* has a slot or opening, *e*, made in its bottom at its lower end, and to the framing *B*, at its lower part, there is attached a series of spouts, *D*, which lead to different bins in the apartment in which the tube *A* is placed.

To the slide *d* of the lower part, *c*, of the

tube *A* there is attached a cord or chain, *E*, which passes over a pulley, *f*, and thence down into the lower part of the building. The cord or chain *E* is attached at its lower end to a drum, *F*, on a shaft, *G*, the latter having a crank, *H*, at one end of it, and a ratchet, *I*, at the opposite end, into which a pawl, *J*, catches.

The ratchet *I* is simply a wheel provided at its periphery with notches *g*, at such a distance apart that when the shaft *G* is turned, and the ratchet *I* engages with each notch, the opening *e* in the bottom of the box *C* will be brought over a spout, *D*.

To the box *C* there is attached a cord or chain, *h*, which extends over a pulley, *i*, at the upper end of an upright, *j*, and has a weight, *K*, at its lower end, said weight having a tendency to keep the box *C* down to the lower part of the framing *B*, as will be fully understood by reference to Fig. 1.

The hopper into which the grain is discharged from the elevators is provided with two discharge-spouts, *C' C''*, and a tube, *a*, connected with each. The spouts *C' C''* incline downward from the hopper at the same degree of inclination from two opposite sides of the latter, and between the two spouts *C' C''*, at their junction with the hopper, there is placed a valve, *L*, which, by being turned or adjusted, may be made to cut off either spout from the hopper. This valve is adjusted by means of a lever, *M*, which is attached to one end of the axis of the valve *L*, and has a cord or chain, *N*, secured to one end of it, said cord or chain passing over a pulley, *k*, and then extending down to the lower part of the building. The lower end of the cord or chain is attached to a pulley, *O*, which has a loaded arm, *P*, connected to it, said arm having a tendency to keep the valve *L* in proper position to close the spout *C''*, and keep the cord or chain *N* at a proper tension. When the valve *L* closes the spout *C'*, the former is kept in proper position by the lever *M*, which is loaded at the end *a* to effect that result.

The operation is as follows: When the box *C* is at the lower part of the framing *B*, the opening *e* in the bottom of the box is in line with or directly over the lowest spout *D*, and the grain will be discharged into the bin with which that spout communicates. When that bin is filled, or the desired amount of grain de-

posited into it, the attendant in the lower part of the building turns the shaft G until the pawl J catches into a succeeding notch g of the ratchet I, and the box C is thereby drawn upward on the framing B, and the opening e brought in line with the next spout D above.

Thus it will be seen that the box C may be drawn up in line with the several spouts and all the bins filled, the part c of the tube A, when fully drawn up, forcing up the part b over the stationary part a, and this adjustment of the parts c b is all done by a person at the lower part of the building, no attendant being required in the bin-loft.

Having thus described my invention, what I claim as new, and desire to secure by Letters Patent, is—

1. The telescopic tube A, provided with the

box C, and placed on an inclined framing, B, which has a series of spouts, D, attached, in combination with the cord or chain E, attached to the box C, and a windlass provided with a ratchet, I, and pawl J, or an equivalent device, for drawing up the box C in line with the several spouts D, all arranged as and for the purpose specified.

2. The valve L, in combination with the two inclined spouts C' C'', and the cord or chain N, arranged with the pulley O, loaded arm P, and the loaded lever M, as and for the purpose specified.

L. P. HARADON.
